UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG.

1,205,145.

Specification of Letters Patent. Patented Nov. 21, 1916.

Application filed February 1, 1915. Serial No. 5,600.

To all whom it may concern:

Be it known that I, ADELMER M. BATES, a citizen of the United States, residing at Chicago, in the county of Cook and State of Illinois, have invented a certain new and useful Improvement in Bags, of which the following is a specification.

My invention relates to valve bags, and has for its object to provide a handle whereby said bags may be manipulated before they are filled during the process of filling, or after they are filled.

It is illustrated in the accompanying drawings, wherein—

Figure 1 is a plan view of a collapsed paper valve bag containing my invention with parts shown in dotted lines. Fig. 2 is a longitudinal section through similar filled bags. Fig. 3 is an enlarged detail view of a bag end showing the handle portion twisted. Fig. 4 is an enlarged detail view of a handle separate from the bag. Fig. 5 is an enlarged detail view of a modification of the handle, and Fig. 6 is a similar view of still further modifications.

Like parts are indicated with the same letter in all the figures.

A, A are the sides of a paper valve bag which has ends B, C, formed by properly 30 folding the bag portions. One of these ends is folded so as to leave an open valve aperture D at one edge of the bag.

E is the interior portion of the handle consisting preferably of a piece of wood of 35 any desired shape, length or cross section on the pointed or beveled ends G, G.

H is the exterior handle portion of any desired shape or material.

The two parts are connected together by 40 a portion which passes through the material of the bag.

J is the exterior portion and as it is shown in Figs. 1, 2, 3, and 4, it consists of flexible cord or rope with the ends J¹, J¹, which pass 45 through the fabric and are made fast to the inner portion E. Where metal is used, this securing part may take the shape of a staple head of which J² lies upon the wooden exterior handle portion H through which the 50 legs of the staple pass. They are twisted at L, the two ends K, K¹ passing through the fabric of the bag and being made fast to the inner handle portion E. The upper edge 55 of the inner handle portion E may be flat as indicated at F.

M is a staple. This may be employed to secure together the inner and outer handle portions when both are of wood. Such a handle may be applied to any kind of a bag which is normally in a closed condition. 60 Such a bag is my valve bag, and here a convenient way of attaching the handle is to insert the inner portion of the handle after the bag is finished through the bag opening, and then place the flexible handle portion in position, its ends passing through the bag body, and then fastening these ends to the interior handle part.

I do not wish to be limited in any particular way to employ the handle, nor to the time when it is applied. If two wooden parts are to be used, the inner portion should be inserted through the valve opening by a kind of carrier or mandrel, and the staple can then be driven in place through the 65 fabric of the bag in such way as to be clenched in the inner handle piece.

In Fig. 6 I have shown a nail M employed in lieu of the metal staple. The handle in such a case, and perhaps in any case, is 70 preferably placed at one side of the end of the bag, or near the side of the bag so that it will lie at one side of the valve channel. This will permit the introduction of 75 the valve filling tube, without its being interfered with by the handle portion. It will also cause the handle portion to lie in such way that, if it be of wood, it will not injure the next adjacent bag in the pile, and in any event it will rise so that it can easily be 80 grasped by the hand.

I desire to have my drawings taken as diagrammatic, but I do not wish to be limited to the particular form, size, shape and proportions of the several parts, as all 85 these may be greatly changed without departing from the spirit of my invention.

The use and operation of my invention are as follows:—When valve bags are employed they are filled by means of a valve filling tube which enters the valve and is withdrawn after the bag is filled. The weight of the material within the bag seats the valve. Such a bag in its usual form is 90 practically without any handle attachment. The ears of an ordinary flour sack due to the sewing process are absent, and so also is the gathered end of the bag which is formed when ordinary bags are tied. Since 95 many persons are accustomed to grasping 100 105 110

such projecting parts and many methods of handling are more or less dependent on the same, it is desirable in many instances to supply some kind of a handle. My handle 5 presents a long interior preferably flat surface against the inner fabric of the bag and it is held in position by the contents of the bag. It is preferably placed as illustrated in the drawings at one side of the end of the bag so that when the bag is filled and laid on its proper side, say with the brand up, the handle will be near the upper surface of the bag and thus will lie against the upper portion of the next adjacent bag so 10 that as the bags are manipulated to and from the pile on which they are being stacked, the handle will always be easily available.

In the case of valve bags it is usually 20 necessary to subject them in the process of filling to some kind of tamping, jiggling or shaking process and this has commonly been done by means of some sort of a jiggling table, the bag being held in the 25 meantime on the filling tube. With a bag having a handle such as we have here illustrated, it is possible to manipulate the bag with or without other means, and particularly with or without those above suggested, 30 so as to shake it or jig it for the purpose of settling or packing the material within the bag. A handle in the case of a valve bag thus becomes an important feature of construction for the purpose of manipulating 35 the bag by hand or by machinery before it is filled or during the filling process or afterward.

Since the valve bag is filled from the upper end the valve being placed at the 40 upper end, it is highly important that the handle should be placed at or near the upper or valve end of the bag, although of course it could be placed at the other end. Two such handles at opposite ends could be used 45 if desired, particularly in the case of valve bags.

In the preferred form of my device the handle is applied to the valve bag after the bag has been otherwise finished.

50 It will be understood that the handle is placed in the bag after the bag has been completed. After these paper bags are delivered, for inserting the handle in a collapsed position, it is necessary to force the 55 inner handle portion into the bag through the valve opening. The pointed end makes this easily possible without danger of tearing the bag or jamming or twisting the

handle piece. After the handle piece is in position, and the bag is ready to be filled, 60 the more or less blunt filling tube is thrust into the valve opening, and since the other end of the handle piece is also pointed, it glides off or is guided off from the filling tube, and there is no possibility of the end 65 of the tube and the end of the handle piece coming into too abrupt contact with one another, such as might result in the tearing of the bag or in the stopping of the movement of the bag on to the filling tube. The 70 load, as the bag is carried by the handle, is of course primarily applied at the center, and experience shows that the pointed ends do not in any way tend to damage the fabric of the bag. 75

I claim:

1. A valve bag provided with a handle at its valve end, said handle consisting of an inner portion, in line with the valve and pointed at one end, an outer portion and a 80 connecting part which passes through the fabric of the bag.

2. A valve bag having a handle at its valve end, said handle being made up of a hand engaging member and an inner anchoring member therefor located within the bag in line with the valve, said member being pointed at one end, said point being adjacent the one side of the member and adjacent the side wall of the bag to guide a 90 filling tube as it enters through the valve gradually along one side of the member.

3. A valve bag having a handle at its valve end, said handle being made up of a hand engaging member and an inner anchoring member therefor located within the bag in line with the valve, said member being pointed at both ends, said points being adjacent the one side of the member and adjacent the side wall of the bag to 100 guide a filling tube as it enters through the valve gradually along one side of the member. 95

4. A valve bag having a handle at its valve end, said handle consisting of an inner portion in line with the valve, a rigid handle piece outside of the bag, and a pivoted connection between them passing through the fabric of the bag. 105

In testimony whereof, I affix my signature in the presence of two witnesses this 110 28th day of January, 1915.

ADELMER M. BATES.
